ELMER P. GOLDSMITH, OF NEWARK, NEW JERSEY, ASSIGNOR TO MILLER & GOLDSMITH, OF NEW YORK, N. Y., A FIRM CONSISTING OF WILLIAM G. MILLER AND ELMER P. GOLDSMITH.

NOVELTY HANDKERCHIEF HOLDER.

Application filed February 26, 1926. Serial No. 90,815.

This invention relates to fancy goods and has particular reference to the construction of novelties such as handkerchief holders or other analogous devices that may be used 5 as gifts, remembrances, place cards, or the like.

Among the objects of the invention is to provide a specially constructed novel means for holding a handkerchief or its equivalent 10 in a peculiarly attractive manner and from which the handkerchief may be removed by the recipient, and after which the holder may be used as an ornament either alone or for the holding of other commodities.

With the foregoing and other objects in view the invention consists in the arrangement and combination of parts hereinafter described and claimed, and while the invention is not restricted to the exact details of 20 construction disclosed or suggested herein, still for the purpose of illustrating a practical embodiment thereof, reference is had to the accompanying drawings in which like reference characters designate the same parts 25 in the several views, and in which—

Fig. 2 is a front elevation of the holder after the handkerchief has been removed.

Fig. 3 is a vertical sectional detail on the line 3—3 of Fig. 2.

Fig. 4 is a horizontal sectional detail on the line 4—4 of Fig. 2.

Referring now more specifically to the drawings, I show my improvement as comprising a base 10 in the nature of a disk of sufficient breadth to render the device self-supporting in upright position, a shank or pedestal 11 fixed in the base and extending 40 upward therefrom, and a head portion 12 fixed to the upper end of the pedestal.

The pedestal may be formed from a simple shank or stick of wood or the like of round construction. The head comprises a face 45 sheet or plate 13 which may be decorated on the front surface to simulate a human face, said sheet being secured against the front side of the top portion of the pedestal stick 11, and being of rounded outline is 50 held in rearwardly bent position by means of a head covering such as a sun bonnet.

The face panel 13 is provided with a downwardly projecting point portion 13^a around which is wrapped a ribbon or other fancy trimming member 15 which may extend in 55 draped relation down to the base 10.

The bonnet structure 14 includes a back portion or hood 14^a which may be pasted or otherwise fastened close against the rear portion of the upper end of the pedestal, 60 thereby serving the better to hold the side wing portions of the face plate 13 in rearwardly directed position. Again, a string member 16 in the nature of a bit of ribbon is brought downward around the bonnet and 65 tied as though under the chin of the head, thereby serving to hold the bonnet in stable position, keeping the face plate 13 in fixed position.

The handkerchief H or other commodity 70 to be supported in display or gift position may be wrapped, draped, or otherwise placed on or around the holder in any suitable position or condition. Preferably I wrap it around the pedestal in graceful folds so as 75 to simulate clothing for the figure, and there pinned so that the drapery is thereby held in reliable position until it is desired for it to be removed from the holder.

It will be apparent that the lacing 15 or 80 drapery which is coiled about the shank or pedestal 11 serves not only as a neat covering therefor but constitutes a fabric through which the fastening pins P may be passed after passing through the handkerchief. 85

I claim:

1. The herein described novelty handkerchief holder comprising a flat horizontal base, a pedestal extending upward therefrom and supported thereby, a head secured to 90 the upper end of the pedestal, a head covering holding the head in proper position, and means including spirally arranged lacing to hold the head covering and the head in position upon the pedestal, said lacing 95 extending around the pedestal downward to the base whereby a handkerchief attached to the pedestal to simulate clothing may readily be pinned in position for display purposes. 100

2. The herein described novelty handkerchief and handkerchief holder representing a dressed doll and comprising a pedestal, pedestal, and constituting the dress for the means to support the pedestal in upright position, a head fixed to the upper end of the pedestal, a head covering including holding means for the same surrounding the pedestal all the way down to the supporting means, a handkerchief draped upon the

5 In testimony whereof I affix my signature.
